UNITED STATES PATENT OFFICE

2,203,929

ATHLETIC SHOE

Isadore Shapiro, Chicago, Ill., assignor to The Athletic Shoe Company, Chicago, Ill., a corporation of Illinois

Application August 18, 1937, Serial No. 159,619

12 Claims. (Cl. 36—59)

My invention relates to athletic shoes and has to do more particularly with shoes of the cleated type, such as are used for outdoor sports, for example, for football, track, golf, climbing, etc.

It has been the practice for many years to reinforce cleated shoes of the type referred to by the insertion of metal plates in the soles in order to prevent the cleats or cleat-attachments from being pushed up into the foot of the wearer, resulting in possible injury to the foot, and also to prevent distortion of the sole as a result of stresses applied by the cleats when the sole is wet and relatively flexible. Various attempts have been made to reduce the weight and increase the flexibility of shoes carrying such metal reinforcing plates.

An object of my invention is to provide a shoe of the type referred to wherein the cleats or traction members are supported by a plurality of metal supporting devices, said supporting devices being sufficiently small and flexible so that the weight of the sole is not greatly increased by said devices nor is the flexibility thereof greatly reduced.

Still another object is to provide a shoe of the type referred to which will be simple and inexpensive in construction, rugged, and entirely satisfactory for the purposes desired.

My invention will be more clearly understood from the appended drawing forming a part of this specification and illustrating certain preferred embodiments wherein,

Fig. 1 is a longitudinal view, partly in elevation and partly in section, of a shoe embodying my invention;

Fig. 2 is a top plan view of the sole with parts cut away to illustrate the cleat supporting devices;

Fig. 3 is a sectional view taken substantially along the line 3—3 of Fig. 1;

Fig. 4 is a view similar to Fig. 3 but illustrating a different type of cleat;

Fig. 5 is a view similar to Fig. 2 but showing a different embodiment of my invention, and

Fig. 6 is a view similar to Fig. 3 showing still another embodiment of my invention.

The shoe comprises an upper 10 and a sole 12 to which is secured a sole tap 13, as by stitching 14. An insole 15 may also be provided in accordance with the usual shoe construction.

In Figs. 1—3, I have shown spikes 18 such as are used in track shoes, and in accordance with the usual track shoe construction no heel tap is provided. The spikes 18 are provided with enlarged heads 19.

Secured to the sole in any suitable manner, and preferably interposed between the sole member 12 and the tap 13, are cleat supporting devices comprising channel shaped members 21 and plates 23. As seen best in Fig. 3, the plates 23 are enclosed within the channel members 21 and are snugly embraced by legs 22 thereof so as to be firmly secured, the heads 19 of the spikes or cleats being secured between the plate 23 and the channel 21, the spike extending through the lower wall of the channel. The channel members may be made of any suitable stock having adequate strength, preferably metal, while the plates 23 are preferably of light weight spring steel.

As seen best in Fig. 2, I may use a single spring plate 23 to reinforce a plurality of cleats while preferably using a single channel member 21 for each cleat, except at the toe of the shoe. It will be understood that the arrangement shown may be varied so long as my object is attained, namely, that of providing adequate support for the cleats while greatly reducing the amount of metal normally carried by the sole in shoes of this type and while avoiding a serious reduction of flexibility. It will be seen that in the arrangement of Fig. 2 the plates 23 which run longitudinally of the shoe are able to flex freely between the individual channel members 21 and thus the sole has a high degree of flexibility. However, the two cleats provided in the toe of the shoe may be supported by a single channel 21 as well as a single plate 23 inasmuch as there is practically no transverse flexing at this point. However, adequate flexibility is provided adjacent the ball of the foot where required.

Fig. 5 illustrates a different arrangement of the supporting elements for a shoe having cleats positioned substantially the same as in Figs. 1 and 2. It will be seen that in the embodiment of Fig. 5 the cleats are supported in pairs by channels 21 extending transversely of the shoe, a single channel being used for each pair of cleats and likewise a single plate 23. By this arrangement also the cleats are given adequate support while at the same time the shoe is free to flex between each of the channels, inasmuch as no stiffening elements are provided in the spaces between the channels.

Fig. 4 illustrates the application of my invention to a football shoe having the usual frusto-conical molded detachable cleat 30. This cleat may, in accordance with one construction, be provided with an embedded nut 32 whereby it is secured to a threaded stud 33 having an enlarged head 35. The head 35 is arranged between the

spring plate 23 and the channel member 21 just as the head of the spike 18 is arranged in the embodiment described above, it being understood that the spring plate 23 and channel member 21 are substantially identical with the corresponding parts described above. A washer 36 is preferably provided adjacent the outside of the sole tap 13 and the stud is clamped to the washer and sole by being spun over as at 38. This type 10 of cleat attachment is more fully described and claimed in my Patent No. 2,098,468, dated November 9, 1937.

Fig. 6 shows another embodiment of my invention as adapted to a cleat 40 of molded frustoconical design having a threaded stud 41 attached thereto, the head 42 of said stud being molded in the cleat 40. In order to attach a cleat of this form to a shoe in accordance with my invention, I provide a channel member 21 embracing a plate 23, said channel and plate being substantially similar to the like numbered devices shown in the other figures, except that the channel has an integral cylindrical neck portion 50 punched therefrom. Such a neck may, of course, 20 be provided in the other embodiments. Seated within the channel member 21 below the plate 23 is a threaded nut or bushing 45 into which is screwed the stud 41. The bushing has a squared head 47 gripped by the channel member 21, 30 whereby the bushing is prevented from rotating.

It will be understood that this type of cleat and attachment may be secured to a shoe according to any of the arrangements shown in Figs. 2 and 5, or in other suitable arrangements.

35 My present invention may be applied to various other types of cleats and to other kinds of cleat attaching devices.

Numerous other variations and modifications of my invention may suggest themselves to those 40 skilled in the art, and hence I do not wish to be limited to the specific embodiments shown and described or uses mentioned except to the extent indicated in the appended claims, which are to be interpreted as broadly as the state of 45 the art will permit.

I claim:

1. In a shoe, a cleat, and means securing the cleat to the shoe comprising a flexible steel plate overlying the cleat to prevent upward movement thereof and means separate from said cleat and plate clamping together the cleat and plate.

2. In a shoe, a cleat comprising a headed portion, and means for securing said cleat comprising a substantially flat member carried by the sole and a plate retained by said member, said head being clamped between said plate and said member.

3. In a shoe having a plurality of cleats each provided with a headed portion, means for attaching a plurality of said cleats to the sole comprising a web like member having a width approximately equal to that of a cleat and a resilient member embraced by said web, said resilient member having a length equal approximately to the space on the sole covered by a plurality of cleats less than the whole number thereof plus the space therebetween, said head being clamped between said resilient member and said web.

4. In a shoe, a cleat having a flat headed member, and means for securing said cleat comprising a web like member embedded in the sole, a plate retained by said web, said head being disposed between said plate and said web. 5

5. In a shoe, a cleat having a threaded extension thereon, and means for securing said cleat comprising a web like member embedded in the sole, a plate retained by said web, and means clamped between said plate and said web threadedly receiving said extension. 10

6. In a shoe, a cleat having a head portion and a stud portion, and means securing the cleat to the shoe sole comprising a resilient plate overlying said head to prevent substantial upward 15 movement thereof and means gripping the head and said plate and having a collar portion extending through at least a portion of the sole to form a support for said stud portion.

7. A cleat attachment for a shoe comprising 20 a flat plate and a channel shaped plate having wings extending around the edges of said first mentioned plate so as to prevent movement of the latter away from said channel shaped plate, one of said plates being perforated, and a cleat 25 having a neck portion extending through said aperture and a head portion disposed between said plates.

8. In a shoe, a cleat attachment as defined in 30 claim 7, wherein said flat plate is resilient and cooperates with a plurality of cleats and wherein there is provided a plurality of channel shaped plates as defined in claim 7, a plurality of such attachments being provided and the portions of the shoe sole between such attachments being substantially free to flex. 35

9. A cleat attachment disposable in a shoe sole comprising a plurality of individual cleats, an elongated, relatively narrow plate for preventing upward movement of said cleats, and a channel-like member engaging the edge and upper portion of said plate and having apertures therein disposed substantially in a straight line, said cleats having neck portions extending through said apertures and head portions disposed beneath said plate. 45

10. A cleat attachment disposable in a shoe sole comprising a plurality of individual cleats, an elongated, relatively narrow plate for preventing upward movement of said cleats, and a channel-like member engaging the edge and upper portion of said plate and having apertures therein disposed substantially in a straight line, said cleats having neck portions extending through said apertures and terminating below said plate. 55

11. In a shoe, a cleat attachment as defined in claim 7 wherein said flat plate cooperates with a plurality of cleats and wherein there is provided a plurality of channel-shaped plates as defined in claim 7, a plurality of such attachments being provided and the portions of the shoe sole between such attachments being substantially free to flex. 60

12. In a shoe, a plurality of cleat attachments as defined in claim 7, the portions of the shoe sole between such attachments being substantially free to flex. 65

ISADORE SHAPIRO.
